UNITED STATES PATENT OFFICE.

WILLIAM M. REYNOLDS, OF NEW YORK, N. Y.

WINDOW-CLEANING CHAIR.

SPECIFICATION forming part of Letters Patent No. 432,643, dated July 22, 1890.

Application filed October 3, 1889. Serial No. 325,883. (No model.)

To all whom it may concern:

Be it known that I, WILLIAM M. REYNOLDS, of New York, in the county and State of New York, have invented certain new and useful Improvements in Window-Cleaning Chairs, of which the following is a specification.

My invention relates to chairs which are used upon the sills of windows when domestics are engaged in cleaning the glasses. The general purpose of such chairs is to diminish the danger attending such operation and to afford a convenient and comfortable seat for the person thus engaged and enable him 15 freely to use both hands. Various forms of chairs of this character have heretofore been devised, and the one which more nearly resembles my invention than any others of which I am aware is that shown in the patent 20 of Crook, No. 410,957, of September 10, 1889, and my invention contemplates certain improvements upon that chair.

The subject-matter claimed is hereinafter specified.

25 In the accompanying drawings, Figure 1 is a perspective view of a chair embodying my improvements; Fig. 2, a side elevation indicating the chair in position upon a window-sill; Fig. 3, an enlarged view of one of the 30 keepers or straps with which the chair is interlocked when in place, and Fig. 4 a detail view of the end of one of the braces which support the chair-bottom; Fig. 5, a detail perspective view of one of the chair-bottom 35 hooks; Fig. 6, a side elevation showing brace-rods running from the sides of the chair-back to the window-frame; Fig. 7, a plan showing the same matter; and Fig. 8 is a view similar to Fig. 6, but showing a high-back chair.

40 The bottom of the chair A is preferably of the rectangular shape shown, and it is provided with a back bow A' and side braces a of any suitable construction. The braces or supports B B are applied to the back bow at 45 b and to the rear edge of the chair-bottom at b', and are then curved inwardly, as shown, and their lower ends formed with rectangular notches or seats b², which embrace the corner of the sill when the chair is in position. The 50 braces are preferably formed with a strengthening-web b³, and may be cast in one piece of malleable iron, or otherwise constructed of

suitable material. At the front of the chair, and preferably at two points, hooks C are secured. They each consist of two horizontal 55 plates c, the upper one being let into a counter-sink in the face of the chair-bottom and the lower one lying against the under face of the chair-bottom, and a hook c' projecting from the front of the chair and formed with 60 a curved outer face. Upon the sill straps or keepers D are rigidly secured by screws or otherwise, and the under faces of the horizontal parts of the keepers are preferably curved to conform to the interior faces of the 65 hooks.

In placing the chair in position the chair-bottom is held vertically with the back projecting into the window, and the hooks C are inserted in the keepers D and the chair 70 turned outwardly until the feet b² of the braces B rest upon and embrace the corner of the sill. I preferably so arrange the braces that the chair-bottom shall have an inclination inwardly toward the window. This 75 relieves the keepers and hooks of a portion of the strain and gives the body of the person a tendency toward the direction of safety. Since the braces B extend from the extreme rear edge of the chair back and bottom to the 80 sill, the weight of the person occupying the chair will be thrown directly upon the edge of the sill, and there can be no tendency for the front edge of the chair-bottom to tilt upwardly and throw a strain upon the hooks 85 and keepers. The shape and location also of the braces B are such that if the person occupying the chair should lean back, so as to throw his weight upon the back bow A', there would be but a slight tendency of the front 90 edge of the chair to tilt upwardly. The main strain would be outwardly about in line with the chair-bottom, and the hooks and keepers are best adapted to resist a strain in that direction. This result is partly due, as above 95 mentioned, to the shape and location of the braces, and also to the fact that the vertical faces of the notches b² in the ends of the braces lie against the vertical face of the sill.

In order to protect the edge of the sill from 100 abrasion or scratches, I preferably line the seat or notch b² with felt, rubber, vulcanized fiber, or other suitable material x.

By providing two hooks and keepers and

two braces B, so that near each side of the chair a brace, hook, and keeper shall be in line, I avoid torsional strain, and thereby further increase the durability and safety of the 5 chair.

As shown in Figs. 6 and 7, rods E may be connected or pivoted at each side of the chair, preferably at the ends or sides of the back bow, and have their hooked ends engage eyes 10 F, secured to the sides of the window-frame. This affords a further measure of safety, and, in fact, makes the occupant of the chair absolutely secure. I may also, as shown in Fig. 15 8, make high-back chairs specially adapted for standing, so that the occupant may readily and without fear reach the uppersash or upper parts of the window-frame. In this case I also provide brace-rods E and eyes F in the sides of the window-frame.

20 I claim as my invention—

1. The combination, with a chair-bottom and devices, as C D, for connecting it with the sill, of a brace or support bolted to the chair-bottom and to the back bow and adapted to 25 rest upon and embrace the corner of the sill.

2. The combination, substantially as set forth, of the chair-bottom and back bow, a brace B, secured directly to the back bow and chair-bottom and having a seat or notch b² 30 for embracing the corner of the sill.

3. The combination of a chair-bottom and

devices for connecting it with the sill, of a support or brace B, connected with the chair-back and the rear of the chair-bottom and extending inwardly under the chair-bottom, its 35 foot being formed with a notch or seat for embracing the corner of the sill.

4. The combination, substantially as set forth, of an ordinary chair-seat having a back, devices for removably connecting the seat of 40 the chair with the window-sill, a support adapted to rest upon the outer part of the sill to sustain the chair-seat, and braces swiveled to the sides of the chair-back and adapted to engage eyes or catches on the sides of the 45 window-frame.

5. The combination, substantially as set forth, of the chair-bottom, devices for connecting it to the sill, a high chair-back, braces or supports connected with the chair-back 50 and rear of the chair-bottom and adapted to rest upon the outer part of the sill, and brace-rods connected with the sides of the chair-back and adapted to engage eyes or catches on the window-frame.

In testimony whereof I have hereunto subscribed my name.

WM. M. REYNOLDS.
